UNITED STATES PATENT OFFICE.

JOHN N. FULLER, OF PHILADELPHIA, PENNSYLVANIA.

ELECTRIC BOILER.

1,270,140.

Specification of Letters Patent. Patented June 18, 1918.

Application filed December 1, 1917. Serial No. 204,908.

To all whom it may concern:

Be it known that I, JOHN N. FULLER, a citizen of the United States, residing at 1858 S. 56th St., Philadelphia, in the county of 5 Philadelphia and State of Pennsylvania, have invented new and useful Improvements in Electric Boilers, of which the following is a specification.

The invention relates to boilers and has 10 for an object to provide an electric boiler for use in rapidly heating a quantity of water, and in fact, generating steam, with a minimum amount of electricity in a short space of time.

15 Among other features, the invention comprehends the use of a heating coil, preferably formed of coiled wire susceptible to an electric current, and which when heated will in turn heat water in the boiler body, to a 20 point where it will be converted to steam.

With these and other objects in view, the invention also comprehends a novel form of arrangement that will take up very little space, and especially within the boiler body 25 will not greatly reduce the fluid area.

30 In the further disclosure of the invention, reference is to be had to the accompanying drawing, constituting a part of this specification, in which similar characters of reference denote corresponding parts in all the views, and in which—

Figure 1 is a side elevation of the boiler, parts being broken away and shown in section, to disclose the underlying structure.

35 Fig. 2 is a fragmentary horizontal sectional view taken substantially along the line 2—2 of Fig. 1.

Fig. 3 is a vertical sectional view taken 40 through the form of plug.

Fig. 4 is a view looking at one end of the plug, and

Fig. 5 is a view looking at the other end of the plug.

Referring more particularly to the views, 45 10 indicates a boiler casing or drum of any desired form, preferably mounted on a suitable base 11 provided with a safety valve 12. The drum or casing 10 has a water inlet 14 and a steam outlet 15, the ends of the cylindrical drum or casing being in the nature 50 of heads 16. Suitably secured within the casing and to the heads 16 are supports or sockets 17 for a horizontally arranged bar 18 made of some non-conducting or insulating material, upon which is suitably wound 55 a coil of wire 19, known as a heating coil;

one end of the wire 19 being secured to one of the heads 16 as at 20, with a wire 21 attached by means of a screw or bolt 22 to the said head, and leading to the source of 60 electric energy, so that it will be seen that the heating coil is practically grounded to the boiler body.

Suitably screwed or otherwise secured to the other head is a plug 23 comprehending 65 a casing 24, through which passes loosely an electrode 25, the inner end of which projects into the casing and has the other end of the wire 19 attached thereto in any convenient manner. The interior of the casing 70 24 of the plug, around the part of the electrode 25 therein, is filled with some non-conducting or insulating material 26, such as, mica, rubber or the like, and disposed upon the electrode or rod 25 are a plurality of 75 disks 27, arranged on each side of an enlarged diamond-shaped portion 28 of the rod or electrode. If desirable, a suitable rubber or other gasket 29 can be arranged adjacent to the inner end of the casing 24, 80 and a disk 30 is arranged to encircle the rod loosely near the outer end of the casing. A threaded element 31 is engaged with the casing 24 to extend therein and bear 85 against the disk 30, so that when the element 31 is screwed up it will compress the material 26 in the casing so as to form a watertight joint, that will prevent leakage of water from the interior of the boiler to the exterior thereof, and also will suitably insulate the electrode 25 from the casing 24, 90 the diamond-shaped part of the electrode serving further to aid in the compression of the material around the inner opening of the casing, as well as around the opening in the 95 disk 30 when the element 31 is screwed up on the casing to compress the material therein, as will be clearly seen.

It will be apparent that when the source 100 of electric energy is connected with the plug 23 to close the circuit with the wire 21, the heating coil will be heated to a degree which will result in the heating of the water in the boiler, and the subsequent formation of steam which can then pass out through the 105 outlet 15.

From the foregoing description it will be seen that the structure described is of a simple nature, comprehends few parts, that can be readily assembled and will not easily 110 get out of order, and although I have shown my particular form of boiler, it will be

understood that I may employ a vertical or horizontal type in accordance with arising conditions.

I claim:

- 5 A heater comprising a casing, inlet and outlet pipes communicating therewith, a support upon the inner side of each end of said casing provided in its upper edge with a recess, a rod entirely inclosed within said casing and having its ends seating within said recesses, a wire coiled about said rod and having one end secured to said casing,
- 10

said casing being of conducting material and said rod being of insulating material, a member threaded through one side of said 15 casing, and a contact member passing through and insulated from said member and connected with the other end of said wire.

In testimony whereof I affix my signature. 20

JOHN N. FULLER.

Witness:

ALFRED T. BRATTON.
